Des. 921

S. W. Gibbs, of Albany, N.Y.
Assignor to
Young and Brother, of same place
Letters Patent, No 921. Dated Aug. 11. 1857.

The Schedule referred to in these Letters Patent and making part
of the same.

To all whom it may concern.

Be it known that I, S. W. Gibbs, in the City of Albany, in the County of Albany, and State of New York, have invented or produced a new and original design for a toy Parlor Stove, and I do hereby declare, that the following is a full and exact description thereof, reference being had to the accompanying drawings and to letters of reference marked thereon.

The drawings represent the stove already mounted showing the front, hearth, end, and top marked respectively 1, 2, 3 & 4; also the end door marked 5.

All ornamental parts of front 1, are claimed as original as also the ornaments on the top 4, and all ornamental parts of hearth 2, ornaments on side and door, or end and door marked 3 & 5; also top ornaments on the top 4, marked 6, and bottom leg, marked 7.

What I claim and desire to secure by Letters Patent is the combination and arrangement of figures and forms as represented, forming the ornamental design of a toy Parlor Stove
